UNITED STATES PATENT OFFICE.

JOHN S. HOUSMAN, OF CHICAGO, ILLINOIS, ASSIGNOR TO GOODMAN MANUFACTURING COMPANY, OF CHICAGO, ILLINOIS, A CORPORATION OF ILLINOIS.

SCRAPER-LOADER APPARATUS.

Application filed April 24, 1924, Serial No. 708,607. Renewed June 29, 1927.

This invention relates to improvements in scraper loader apparatus, and more particularly to a reciprocably operated scraper adapted for use in restricted passageways, as for instance, in gathering coal in the longwall system of mining.

The principal object of the invention is to provide an improved construction for a scraper of the class above described.

10 The invention may be best understood by reference to the accompanying drawings, in which:

Figure 1 is a plan view of a scraper constructed in accordance with my invention;

15 Figure 2 is a side view of the scraper with parts broken away;

Figure 3 is a diagrammatic view, showing the application of the scraper to a typical longwall mining operation.

20 Referring now to the details of the drawings, my improved scraper is made up of two wall portions, one portion 10 being relatively longer than the other portion 11. These two portions are movable relative to 25 each other, for this purpose being hinged at the meeting ends by suitable means such as a pin 12. Outward spreading movement of the walls is limited by suitable means, such as a chain 13. The scraper thus formed is 30 preferably bottomless although the lower margins 10^a and 11^a of the respective side walls 10 and 11 may be turned inwardly to provide cutting edges to assist in gathering loose material.

35 The draft ropes for reciprocably operating the scraper comprise a head rope 14 and a tail rope 15. The head rope is connected to the forward end of the longer wall portion 10, this end being curved inwardly as indicated at 16, and as herein shown, the point of connection of the head rope 14 is offset with relation to the side wall 10 approximately the same distance as the point of 40 pivotal connection with the other side wall 11 at the rear end of the scraper. In the preferred form shown, the curved connecting portion 16 is made up of a pair of members 17 and 18 which diverge from each other in a vertical plane, the upper member 17 extending along the entire length of the side wall 10 to provide a reinforcing strip therefor, and the lower member 18 being connected with the front margin of the side wall 10. The tail rope 15 is attached to the shorter 50 wall portion 11 adjacent the point of pivotal 55

connection of the two wall portions as shown in Figure 1, the arrangement being such that the scraper will have a tendency to be maintained in open position while being drawn rearwardly by means of the tail rope, although this point of pivotal connection is near enough to the hinge to permit the shorter portion 11 to be readily collapsed in case 60 obstructions are encountered during such rearward movement.

65 The use and operation of the device is as follows:

Referring to the diagram in Figure 3, the scraper is shown as applied to the longwall system of mining, in which a working face 70 20 is being advanced by successively breaking down portions of the coal into piles of loose material adjacent the face, as indicated at 21. The drawing illustrates a common condition encountered in longwall mining, 75 namely, one in which it is necessary to provide a series of mine props 22, 22, quite close to the working face in order to support the roof while the coal is being mined. The area indicated by boundary 23 beyond the line 80 of props 22, 22, represents the portion which has been exhausted and abandoned and usually has been substantially closed by dropping of the roof.

Referring more particularly to the use of 85 my improved scraper under these conditions, it will be seen that I provide a plurality of guide sheaves 25, 25, suitably arranged at opposite ends of the working face to control the reciprocal movement of the scraper along 90 the face whereby the loose material may be gathered and transported to a point of loading, as for instance in the entry 26 having tracks 27, 27, for mine cars. A suitable hoist 28 is provided, having a pair of drums 29 and 95 30, operatively connected respectively with the head and tail ropes of the scraper. As shown herein, the hoist is arranged in the entry 26 although it may be placed in any desirable manner. It will be seen that the peculiar 100 shape of the scraper is particularly advantageous under these conditions, the shorter wall portion 11 being arranged facing the working face with its front margin 31 forming the cutting edge to enter the loose material. The longer wall portion 10 has a tendency to be maintained in a position approximately parallel with the working face 105 while the scraper is in operation and by reason of the continuous curved portion 16 110

to which the head rope 14 is connected, the scraper may ride smoothly over the mine props 22, 22, when the scraper is deflected laterally into contact therewith during the loading operation. The pivoted portions are automatically opened during the forward movement by contact with the loose material. The arrangement of the tail rope connection also tends to open the scraper while it is being drawn rearwardly, although as before pointed out, the scraper is readily collapsible when obstructions are encountered, and especially when it is necessary to pass through relatively restricted places, for example after a new portion has been dislodged from the working face so as to leave a very restricted passage between the newly set mine props and the pile of loose material.

Although I have shown and described one form in which my invention may be embodied, it will be understood that the arrangement and construction of the various parts may be altered without departing from the spirit or scope thereof. I do not wish to be understood, therefore, as limiting myself to the particular construction illustrated herein, excepting as limited in the accompanying claims.

I claim as my invention:

1. In a scraper device of the class described, the combination of two wall portions of unequal length, movable relative to each other, means limiting the relative movement of said wall portions, and a draft rope connected directly to the forward end of one of said wall portions.

2. In a scraper device of the class described, the combination of two wall portions of unequal length, movable relative to each

other, means limiting the relative movement of said wall portions, and a draft rope connected to the forward end of the longer of said walls, said end being offset inwardly.

3. In a scraper of the class described, the combination of two wall portions of different lengths pivotally connected at adjacent ends, means limiting the pivotal movement of said wall portions in each direction, and a draft rope connected to the forward end of the longer of said portions, said forward end being offset inwardly substantially in alignment with the point of pivotal connection of said wall portions.

4. In a scraper device of the class described, the combination of two wall portions of unequal length, movable relative to each other, means limiting the relative movement of said wall portions, a draft rope connected directly to the forward end of said wall portions, and another draft rope connected with the shorter wall portion.

5. In a scraper of the class described, the combination of two wall portions of different lengths pivotally connected at adjacent ends, means limiting the pivotal movement of said wall portions in each direction, and a draft rope connected to the forward end of the longer of said portions, said forward end being offset substantially in alignment with the point of pivotal connection of said wall portions, and a tail rope connected to the shorter of said wall portions adjacent the pivotal connection thereof.

Signed at Chicago, in the county of Cook and State of Illinois, this 16th day of April, 1924.

JOHN S. HOUSMAN.
